DRIVING DEVICE FOR PILE MEMBERS
Ludwig Müller, Heinrich-Heine-Str. 41,
Marburg an der Lahn, Germany
Filed Apr. 14, 1960, Ser. No. 22,164
Claims priority, application Germany Apr. 25, 1959
6 Claims. (Cl. 175—55)

The present invention relates to a device for driving or lifting tubular members, piles, sheet piles, etc. and similar members to be driven or lifted. The term "pile member" hereinafter sometimes used is intended to encompass all structures that can be driven or lifted with a device of the kind to which the present invention relates. More particularly, the invention relates to a device for driving and lifting of pile members utilizing dynamic oscillatory forces acting in the driving direction or the opposite direction which are generated by means of a vibratory exciter including rotary masses.

There are known installations of the general kind above referred to, in which the exciter is mounted on a frame structure and slidable along the length thereof and in which static forces directed either in the driving direction or opposite thereto are applied to the member to be driven or lifted by subjecting said member to load or pull forces whereby the power output of the device producing the static forces is adjustable during operation. More specifically, the static forces are produced by means of a heavy frame structure on which a pile driver is mounted and a rope winch mounted at the base of the frame structure, the traction rope of the winch being linked by spring means to the driven member.

It is an object of the invention to provide a novel and improved device of the general kind above referred to which affords the advantage that a heavy frame structure for supporting the pile driving device is not required. Such heavy structure is necessary in heretofore known installations since the frame structure has to sustain laterally directed forces caused by the rope pull of the winch. With the installation, according to the invention, it is merely necessary to hold the frame structure in a selected location, and the means used for so holding the frame structure are not subjected to the forces that are used to effect the actual driving or lifting operation.

According to the invention the aforementioned objects, features and advantages and other objects, features and advantages which will be pointed out hereinafter, are attained by providing a comparatively light frame structure movable on a support base in reference to a pile member to be worked. On this frame structure a power driven transmission means on the frame structure is coupled with the vibration exciter slidably guided along the frame structure and acting upon the pile member to be driven or lifted in order to apply load and pull forces thereto.

The frame structure is preferably equipped with mounted hooks and eyes for attaching the load hook of a derrick or the jig boom of a hoist to the frame structure.

The transmission means by means of which the load or pull forces are applied to the exciter and through it to the pile member may comprise endless chains or ropes which are guided over pulleys mounted at the top and the base of the frame structure and are driven by a motor, preferably mounted at the base of the frame structure.

Instead of using an endless rope or chain drive a pinion-gear rack drive may also be provided. The rack then preferably extends along the length of the frame structure and the pinion is mounted on the exciter.

To steady the frame structure in the selected location a platform for placing ballast weights thereon may be provided at the base of the the frame structure.

In the accompanying drawing several preferred embodi-

ments of the invention are shown by way of illustration and not by way of limitation.

FIG. 1 is an elevational view of a pile driving device according to the invention, the transmission means on the frame structure being shown as a chain drive.

FIG. 2 is an elevational view of a modification of the pile driving device, the transmission means being shown as including a pinion and rack drive.

FIG. 3 shows a pile driving device according to FIG. 1 hooked to a track-laying vehicle, and

FIG. 4 is an elevational view showing the pile driving device of FIG. 1 laid down for transport on a flat truck.

Referring first to FIG. 1 in detail, the installation according to this figure, comprises an upright frame structure 1 mounting at its base a running wheel 2 resting on the ground 3. Guide rails 4, 4' extend along the length of the frame structure for guiding a yoke 5. The yoke is slidable up and down along the rails guided by rollers 6, the driving direction is being indicated by R and the lifting direction by Z. Yoke 5 has a laterally extending arm from which is suspended by means of compression springs 8 the vibratory exciter 7. The exciter is only diagrammatically indicated; it should be visualized as comprising a pair of rotary masses 7a and 7b which are rotated synchronously but in opposite directions. The pile member 9 indicated as a pile shaft is clamped to the exciter by any clamping means suitable for the purpose.

In order to transmit static forces in the direction R or Z from the frame structure to the exciter, a power driven transmission means is provided on the frame structure. This transmission means comprises endless chains or belts 11, 11' which are guided over pulleys 12 at the top and the base of the frame structure. The chain drive should be visualized as being driven from a drive means 10 diagrammatically indicated at the base of the frame structure. The chain drive is coupled with the yoke by means of a suitable locking or clamping means 13. As is evident, yoke 5 can be lowered or lifted by driving chains 11, 11' in one or the other direction. Movement of the yoke in the direction R will apply to pile member 9 a static force in the driving direction and similarly lifting of yoke 5 will apply to member 9 a static force in the lifting direction. As is apparent, the static forces will coact with the dynamic oscillatory forces applied to member 9 by means of the exciter.

A platform 14 is provided at the base of the frame structure for placing thereon ballast weights 15. A jig boom 16 from which a load hook 17 depends, is rotatably mounted at the top of the frame structure. The frame structure 50 is further equipped with one or several hooks and eyes 18', 18'' and 18''' for hooking the entire installation to a derrick or hoist 19 as is shown in FIG. 2.

In FIG. 2 corresponding components are designated with the same reference characters as in FIG. 1 but indexed with the letter a.

The structure of FIG. 2 is similar in principle to that of FIG. 1 except that the endless chain or rope drive of FIG. 1 is replaced by a pinion-rack drive. Rack 23 extends along the length of the frame structure and 60 coacts with a pinion 24 mounted on yoke 5a. The yoke also supports the drive motor 25 for the gear drive. As is evident travel of pinion 24 along the rack will produce static forces which are transmitted to the pile member 9a to be driven or lifted.

65 The frame structure and all the parts supported thereby are held in position by spacer rods 26 hooked in eyes 18a'' and 18a''' and to the derrick.

The arrangement of FIG. 3 is evident from the previous discussion. According to FIG. 3 the entire driving device 70 is hooked to a track-laying vehicle 21 such as an earth moving machine. The boom 20 of the vehicle is hooked to eye 18b''' on the frame structure.

In the arrangement of FIG. 4 the entire installation is laid down for transport and is placed with its upper part upon a platform 27 of a truck 28. The protruding part of the frame structure is supported by a running wheel 2c'.

While the invention has been described in detail with respect to certain now preferred examples and embodiments of the invention it will be understood by those skilled in the art after understanding the invention, that various changes and modifications may be made without departing from the spirit and scope of the invention, and it is intended, therefore, to cover all such changes and modifications in the appended claims.

What is claimed as new and desired to be secured by Letters Patent is:

1. A device for driving and lifting respectively a pile member, said device comprising an upright frame structure resting upon a support base, a yoke, guide and drive means supported on the frame structure for guiding and driving said yoke up and down along the same, a vibration exciter including rotary means for generating dynamic alternately directed forces, spring means yieldably suspending said exciter from said yoke, said exciter being connectable in force-transmitting engagement with a pile member to be driven and lifted respectively for applying the generated dynamic forces thereto, and coupling means for fixedly coupling the yoke to the guide and drive means in a selected position in reference to the exciter to vary thereby the tension of said spring means, said yoke and said guide and drive means constituting a static load acting upon the exciter and the pile member in accordance with the selected position of the yoke.

2. A device according to claim 1 wherein said guide and drive means comprise an endless cable drive mounted on the frame structure, and said coupling means comprise a clamping member secured to said yoke and clamped to the cable drive.

5

3. A device according to claim 1 wherein said guide and drive means comprise a rack secured to the frame structure and extending along the length thereof, and a pinion secured to the yoke and engaging said rack.

4. A device according to claim 1 wherein said frame structure is mounted on a movable support base, said base including a platform, and wherein ballast weights are placeable upon said platform.

5. A device according to claim 1 wherein a transport roller is provided at the base end of said frame structure for moving the same in reference to a pile to be driven or lifted.

6. A device according to claim 1 wherein said guide and drive means comprise a rack secured to the frame structure, a pinion secured to the yoke and engaging the rack, and a drive motor mounted on the said yoke and coupled to the pinion for displacing the yoke up and down in reference to the rack.
